HERBERT G. IRWIN, OF AMARILLO, TEXAS.

CARBIDE AGITATOR FOR ACETYLENE GENERATORS.

Application filed January 26, 1925. Serial No. 4,935.

My invention relates to improvements in acetylene generators for welding purposes of the carbide to water type in which an automatically controlled valve regulates the gravitation of granular carbide from a container into a water container, the rate of carbide feed being determined by the rate of consumption of the acetylene generated; and the objects of my improvements are, 10 first, to agitate the carbide in the vicinity of the feed valve to prevent banking or clogging of the carbide so the feeding of same may be constantly maintained and uniformly governed to generate acetylene in proportion to the rate of the consumption of acetylene; second, to use the flow of the acetylene drawn from the generator in use for operating means connected and arranged with the acetylene outlet and carbide feed mechanism for agitating the carbide.

These stated objects and such other objects as will incidentally appear in the course of the following description are attained in the several forms of mechanisms illustrated in the accompanying drawings, and the invention resides in certain novel features which will be pointed out in the claim following the description.

30 In the accompanying drawings:—

Figure 1 is a vertical section of an acetylene-generator having an internal carbide hopper illustrating one form of feed mechanism equipped with my invention.

35 Figure 2 is a vertical section of an acetylene-generator having an external carbide hopper and illustrates another form of valve feed mechanism equipped with my invention.

40 Figure 3 is a vertical section of the upper portion of an acetylene-generator illustrating still another form of valve feed mechanism equipped with my invention.

Figure 4 is a vertical section of the upper portion of an acetylene-generator similar to that shown in Fig. 1 and it shows my invention applied in a modified way.

45 Figure 5 is a vertical section of the upper portion of a generator having a carbide feed similar to that shown in Fig. 1

the feed control being omitted and it shows still another method of applying my invention.

Figure 6 is an enlarged view of the valve stem of the feed mechanism shown in Fig. 55 1. The vibrator is mounted on the valve stem and consists of a multiple diaphragm, which is shown in section.

Figure 7 illustrates the several units of the diaphragm assembly shown in Fig. 6 in cross section. The units being spaced apart and arranged in the manner in which they assemble.

Figure 8 is an enlarged view of a valve stem similar to that shown in Fig. 6. It 65 is equipped with a modified form of vibrator which is shown in section.

Figure 9 is an enlarged view in vertical section of the agitator mechanism embodied in the feed shown in Fig. 2. The vibrator 70 being mounted on the valve stem and consists of a multiple diaphragm.

Figure 10 is a view of a valve stem that is interchangeable with the valve stem shown in Fig. 9. The vibrator consists of 75 single diaphragm carried in a case which is shown in section.

Figure 11 is a detail view of the flash-back safety tank of the generator shown in Fig. 2. A portion of its wall being broken 80 away for illustrating the water seal.

Figure 12 is an enlarged sectional view of a type of check valve that may be placed in the acetylene outlet pipe to interrupt the gas flow for energizing the vibrator.

Figure 13 is a sectional view of a ball type of check valve that may be placed in the acetylene outlet pipe for interrupting the gas flow.

Figure 14 is a sectional view of one form 90 of liquid type interrupter that may be connected with the acetylene outlet pipe for interrupting the gas flow.

Figure 15 is a sectional view of another form of a liquid interrupter.

In detail:

Similar numerals refer to similar parts throughout the several views.

My invention may be applied to any valve feed generator and the several forms of

feed mechanisms shown herein are for illustrative purposes. The water container 1, may be of any suitable form and the carbide container 2, may be of either internal or 5 external type and of various shapes common in generator design. The feed valve 3, may be any of the various types that operate above or below the mouth or outlet 4, of the carbide container. In the automatic valve feed generator a diaphragm of some form is commonly used to control the feed valve and is connected with the valve by various forms of gearing. The control diaphragm being energized by a 10 spring or the variation of gas pressure in the generator or both for governing the feeding of carbide.

The feed control diaphragm 5, shown in the drawing is the usual rubber and fabric 20 type mounted in a housing composed of two cup shaped sections 6 and 7. The section 7 being secured to the generator body and communicates with the interior of the generator at 8. The control diaphragm 25 forms a flexible partition in said housing and its outer marginal edge is clamped between the flanges 9 9, of the housing in the usual manner. The section 6 of the housing communicates with the atmosphere through 30 the aperture 10, and in this section of the housing is positioned the usual feed spring 11, to press against the outer side of the diaphragm when the hand crank 12, is screwed down to set the feed in operation.

35 In the present forms of valve gearing the spiral spring 13, tends to hold the feed valve closed. In Figs. 1, 4 and 5 this spring is shown about the upper end of the feed valve stem 14, while Fig. 3 shows the spring on 40 the upper end of the rod 15, which rod is connected with the feed valve through the link 16. The spring 13A, in Fig. 2 serves in the same capacity as the spring 13 except it is positioned to press downwardly on the 45 inner end of the lever 17, to close the feed valve. The broad flat nut 18, on the upper extremity of the feed valve stem 14 and rod 15 in Figs. 1, 3 and 4 abuts the under side of the control diaphragm and the spring 50 13 presses upwardly against the under side of the nut to close the feed valve when the control diaphragm is flexed upwardly by gas pressure or when the feed spring 11 is released.

55 Upon reference to Figs. 1 and 4 it will be seen that by screwing the hand crank 12 downwardly compressing the feed spring 11 against the upper side of the feed control diaphragm 5 causes the diaphragm to 60 yield downwardly, and through its pushing the valve stem 14 downwardly will open the feed valve 3 and allow some granular carbide 19, fall into the water 20, in the lower portion of the water chamber 1 will cause 65 acetylene to be generated. Acetylene will

flow by the feed valve into the carbide container, hence into the lower section 7 of the diaphragm housing to the under side of the control diaphragm, and when the acetylene pressure reaches a point to overcome the pressure of the feed spring the diaphragm will flex upwardly as the pressure increases, allowing the spring 13 to draw the feed valve sufficiently closed to cut off the flow of carbide. Now if some 70 of the acetylene is used from the generator, the acetylene pressure on the under side of the control diaphragm will be diminished allowing the diaphragm to yield downwardly under influence of the feed spring some 75 what in accordance with the decrease in the acetylene pressure, until the feed valve is opened sufficient to allow more carbide fall into the water, and in this manner 80 automatically maintaining a pressure in 85 the generator until all the carbide in the carbide container is used up.

The operation of the form of feed shown in Fig. 3 is similar to that of Figs. 1 and 4. The rod 15 leading from the control diaphragm is connected with the feed valve through the link 16 having pivots 21 and 22. Under influence of the feed spring 11 the rod 15 moves downwardly to open the feed valve. Acetylene pressure on the under side 90 of the control diaphragm counter-acts the effect of the feed spring on the rod 15 and the spring 13 moves the rod upwardly closing the valve.

95 The operation of the feed shown in Fig. 2 differs slightly from the feeds previously described, in that the feed valve is positioned above the carbide outlet 4 and moves upwardly to open. The operating motion of the feed spring 11 and the control diaphragm being reversed by the lever 17 which is mounted on the pivot 25. The outer end of the lever being connected with the control diaphragm through the push-rod 23.

100 The foregoing description of the several forms of carbide feeds taken in connection with the drawings is intended as an exemplification only, as my invention is best applied to the valve feed type of generator. While the ordinary acetylene generator 105 with a diaphragm controlled valve feed is automatic in operation, there is some variation in the acetylene pressure, which, however, is required for the feed to function. In using a popular size of carbide known 110 on the market as $\frac{1}{4} \times \frac{1}{2}$, an ordinary valve feed is somewhat intermittent and the variation of the acetylene pressure is accordingly augmented to a degree that is objectionable for welding purposes. The increased variation of the acetylene pressure 115 being due to the irregular size and shape of the grains of this size of carbide, together by its clogging or banking in the reduced portion of the carbide container ad- 120 125 130

jacent the feed valve. That is the rough touching carbide grains seem to congest in the small end of the conical carbide hopper bottom in the vicinity of the feed valve. 5 This requires an increased opening movement of the feed valve at times to start the flow of carbide which represents considerable reduction of the acetylene pressure. Then when the flow of carbide has started, 10 much passes the feed valve before there is enough acetylene generated to energize the control diaphragm whereby, to close the feed valve. The excess acetylene generated thereby brings the pressure above normal 15 which hinders the welder, in that he is compelled to stop welding and readjust his torch. This objectionable feature of the valve feed generator may be eliminated by keeping the carbide in the vicinity of the 20 feed valve in constant motion or slightly moved at close intervals while acetylene is being used from the generator. The result being a constant and uniform feed of carbide, and acetylene is generated in proportion 25 to the rate at which acetylene is consumed, thereby reducing the variation of the pressure for controlling the feed to a minimum. I accomplish this by providing means in the acetylene outlet pipe to interrupt at 30 close intervals the outward acetylene flow so as to slightly fluctuate the pressure of the flow and placing a medium in communication with the outlet pipe for registering the fluctuating pressure of the flow in a form 35 of vibrant energy and transmitting said energy to the carbide feed mechanism or means in contact with the carbide in the vicinity of the feed valve to effect the agitation of the carbide about the feed valve. 40 Of course in applying my invention to various forms of feeds requires modification in minor details as well alteration in the feed mechanism, the acetylene outlet line etc.

45 In Fig. 1 for an instance the acetylene outlet pipe 26, enters the water container some distance below the water level and extends upward adjacent the inner periphery of the container to a point near the carbide container. To the outer end of the outlet pipe is connected a vertical check valve 34, and the usual flash-back safety tank 35. On the inner end of the outlet pipe I provide an interrupter comprising an angle check valve 50 27, (see Figs. 12 and 13) for slightly pulsating or interrupting the outward acetylene flow in the pipe. In communication with the outlet pipe a slight distance above the water level is located a tubular nipple 28, to which one end of a flexible tube or hose 29, is secured. The hose extends toward the center of the water container and bends upward and is secured to a second nipple 30, that projects downward from the center of the feed valve. The hose being flexible,

yields to the operation of the feed valve and serves a purpose which will appear presently. The vibrator 31, is located on the valve stem within the carbide container a slight distance above the feed valve, and 70 that portion J, of the valve stem from the vibrator down to the feed valve including the hose nipple 30 is tubular, so the vibrator through the medium of the hose 29 will be in constant communication with the acetylene outlet pipe. The valve stem guide 33, is carried by a bracket 36, that extends across the carbide container and to the lower edge of the bracket centrally with the guide a shield or housing 33A, is suspended. Said 75 housing extends downwardly over the vibrator to a point near the bottom of the carbide container to provide a space wherein the vibrator may move up and down with the valve stem, the carbide passing under 80 the lower edge of the housing to the feed valve and outlet. The vibrator in this instance is composed of a series of thin ring like metallic plates 32, having edge flanges A and B, comprising binders adapted to be 85 bent over a corresponding plain edge C and D, of the adjacent plate for joining the several plates together. The several plates may be seen arranged in the manner in which they assemble in Fig. 7. (See Fig. 6 also.) 90 The lower end of the section K, of the feed valve stem is secured to the center of a relatively thick disk 32A, and the upper end of the tubular section J is secured to the center 95 of a second disk 32B, which is identical in 100 configuration with the disk 32A. The upper and lower plates of the vibrator structure have their flanges B B bent over the edge portion of said disks to join the two sections of the valve stem with the vibrator. Solder being used to secure all joints insuring a gas tight structure. To prevent undue 105 expansion or possible fracturing of the vibrator should any excess pressure occur in the outlet pipe, a case 31A, is provided to 110 enclose and protect the vibrator. The case fits loosely over the vibrator with its upper side lying upon the disk 32A of the structure, there being enough clearance between the disk 32B and the lower side of the case 115 for the vibrator to operate without striking the case.

When acetylene is used from the generator it enters the outlet pipe 26 through the interrupter valve 27, flows through the vertical check valve 34 into the flash-back tank 35 and upward through the water 39, contained in said tank and through the cut-off valve 38 into the torch line, not shown. The interrupter valve 27 serves to fluctuate 120 the pressure at which the acetylene flows in the outlet pipe and by reason the interior of the vibrator being in communication with the outlet pipe and its exterior exposed to the acetylene pressure in the generator, the 125 130

vibrator is made to slightly contract and expand in harmony with the frequency of the transformed pressure in the outlet pipe. Due to the location of the vibrator the 5 energy thereof is transmitted to the carbide about the outlet 4 through the lower section J of the valve stem and feed valve. Under influence of vibration granular carbide responds immediately to the regulating 10 movements of the feed valve, which results in the feed flow being accurately controlled with respect to the consumption of acetylene.

The valve stem shown in Fig. 8 is 15 equipped with a modified form of vibrator and may be used in the feed mechanism shown in Fig. 1 instead of the valve stem shown in Fig. 6. In this form of vibrator the case 31B, consists of two cone shaped 20 sections E and F, between which is clamped a flexible diaphragm 32C, of the usual rubber and fabric type. The diaphragm forms a flexible partition in the case and the tubular section J of the valve stem has its upper 25 end secured to the center of the diaphragm. The upper section K of the valve stem has its lower end secured to the point of the upper section F of the diaphragm case. The sides of the lower section E of the dia- 30 phragm case terminate in a tubular guide G, that keeps the lower section of the valve stem in alinement with the upper section of the stem. Acetylene in the outlet pipe is admitted to the upper side of the diaphragm 35 through the hose 29 and the lower section J of the valve stem, while acetylene in the generator is admitted to the under side of the diaphragm through the guide G and openings H, in the lower section of the case. 40 It will be seen that by diminishing the acetylene pressure on the upper side of the diaphragm the pressure on the under side thereof will flex the diaphragm upwardly, lifting the lower section of the valve stem 45 and feed valve. Then to equalize or almost equalize the pressure on the upper side of the diaphragm with that on its under side, the weight of the lower section of the valve stem will flex the diaphragm downwardly and if 50 this is carried on repeatedly at close intervals as by the action of the interrupter valve 27 on the outward acetylene flow in the outlet pipe, the diaphragm and the lower section of the valve stem will be put in vibration. 55 The valve placed in the outlet pipe to interrupt the acetylene flow, will be understood to be any type of valve that will operate under influence of the acetylene flow whereby, to check the flow for a short period 60 of time repeatedly. Thus it is obvious that the fluctuation of the acetylene pressure in the outlet pipe due to the frequent checking of the acetylene flow energizes the vibrator. The fluctuation of the pressure in the outlet 65 pipe to a certain extent does not hinder good

operation of the welding torch. The inter- 70 ruptor valves shown in Figs. 12 and 13 have bodies adapted for connecting in the angle of a pipe, but if desirable to locate the inter- 75 ruptor in a vertical or horizontal section of the outlet pipe a valve adapted to work in a vertical or horizontal position may be used. It is necessary that the oscillator or valving member whether a ball 27A, or a cone 27B, or of any other form, be fitted accurately 75 to its seat so as no gas will pass without unseating the member. In installing the valve interrupter it is necessary that it is arranged in the outlet so the valving mem- 80 ber will move away from its seat in the direction of the flow.

In Fig. 2, the vibrator 31 is located on the feed valve stem also and in a manner similar to that shown in Fig. 1. The structure comprising the vibrator being the same 85 as that shown in Figs. 6 and 7. The valve stem in this form of feed is comparatively short and is suspended from the inner end of the lever 17 by a pivot 25A. The upper section of this valve stem is tubular and is 90 designated by letter M, while the lower section comprising a rod is designated by letter N. The upper end of the section M of the valve stem is angled to provide a nipple 14A, to receive one end of the hose 29A, that 95 extends lengthwise under the lever 17 to a second nipple 39A, screwed into the inner end of a sleeve coupling 39, which latter is secured in the outer end wall of the lever housing 17A. A pipe 40, has one end 100 screwed into the outer end of the coupling 39 and bends downward to unite with the acetylene outlet pipe 26 through the union 40A, of the angle fitting 26A, in the latter pipe. (See Fig. 9.) The interrupter valve 105 27 is of horizontal form in this instance and is located in the horizontal section of the outlet pipe between the angle fitting 26A and the generator body. It is preferred to locate the interrupter outside of the generator 110 where it will be accessible for cleaning or otherwise in case it should fail to operate properly. The lower end of the outlet pipe connects with a horizontal check valve 34A, and the usual flash-back safety tank 35. 115 (See Fig. 11.) The vibrator 31 communicates with the acetylene outlet pipe 26 through the upper section M of the valve stem, the hose 29A and the pipe 40. The energy of the vibrator is carried by the lower section N 120 of the valve stem and feed valve to the carbide in the vicinity of the valve and outlet 4, with obvious results.

The valve stem shown in Fig. 10, may be 125 used in the place of the stem shown in Figs. 2 and 9. The vibrator here is the same as that shown in Fig. 8, the upper and lower sections of the valve stem being reversed, that is, the upper section M is tubular while the lower section N comprises a rod which 130

has its upper end secured to the center of the diaphragm 32C.

In Fig. 3 the vibrator 31 is substantially the same as that shown in Figs. 8 and 10. Instead of being located on the valve stem, the vibrator is positioned on the inner horizontal portion of the acetylene outlet pipe 26 directly under the end 16A, of the horizontal link member 16 of the feed mechanism. A post 41, secured to the center of the diaphragm 32C connects the diaphragm with said link member at the pivot 16A. Spiral springs X, are positioned in the vibrator case on opposite sides of the diaphragm to carry the strain exerted by the feed mechanism on the post 41 in actuating the feed valve. The lower section E of the vibrator case in this instance communicates with the outlet pipe at 31C, where acetylene is admitted from said pipe to the under side of the diaphragm, while acetylene in the generator is admitted to the upper side of the diaphragm through the opening in the upper section F of the case through which the post 41 projects. The interrupter valve 27 is fitted on the inner extremity of the outlet pipe to interrupt the acetylene flow as it enters the pipe. The diaphragm of the vibrator is operated by fluctuation in pressure of the interrupted acetylene flow. The energy of the vibrator is expanded in the link member 16 and the feed valve, thereby agitating the carbide about the feed valve and outlet when acetylene is used from the generator.

In Fig. 4 the inner portion of the acetylene outlet pipe is disposed vertically adjacent the inner wall of the generator body. The feed valve stem projects some distance below the feed valve and is reduced somewhat at the end. A vibrator 31 similar to that shown in Fig. 3 is positioned on the inner portion of the outlet pipe in communication therewith and in a horizontal plane with the reduced end 14C, of the valve stem. A flexible coupler 42, connects the vibrator diaphragm 32C with said reduced end of the valve stem. The coupler being flexible yields to the feed motion of the feed valve. The interrupter valve 27 is fitted on the upper extremity of the outlet pipe to interrupt the acetylene flow in the pipe, whereby to energize the vibrator. By this arrangement the vibrator functions to shake the feed valve 3 laterally through the coupler 42 when there is an outward flow of acetylene in the outlet pipe.

In Fig. 5 the acetylene outlet pipe 26 enters the generator at the top to one side of the carbide feed mechanism and extends down through the carbide container 2 into the upper portion of the water container 1 a short distance. The vibrator 31 is secured to the lower extremity of the outlet pipe in communication therewith. The interrupter valve 27 is located between the vibrator and the

bottom of the carbide container on a tubular nipple that projects from the outlet pipe. The mouth 4A, of the carbide container is relatively large in this instance and a shaker comprising a cone shaped cup 43, is suspended directly under the mouth by a pair of arms 44 and 45, projecting from opposite sides of the cup. The arm 44 has its outer end pivoted to the lower end of a bracket 44A, that extends downward from the bottom of the carbide container. The outer end of the arm 45 is connected with the vibrator diaphragm 32C by a depending connector 45A. A carbide outlet 4 is provided in the bottom of the shaker cup 43 and the feed valve 3 seats in said outlet. Carbide from the carbide container enters the shaker cup through the mouth 4A by gravity and the feed valve regulates carbide from the shaker cup into the water container. Acetylene from the water container enters the outlet pipe through the interrupter valve 27, which latter interrupts the flow for energizing the vibrator. The vibrator functions to operate the shaker 43 by moving the arm 45 in successive motion up and down when there is a flow in the outlet pipe.

An ordinary ball check valve of either cone or ball type placed in the acetylene outlet pipe so the valve member will open in the direction of the flow, the valve member will click continually or vibrate upon its seat under influence of an outward flow of acetylene, serves to interrupt the flow for energizing the vibrator, and may be used on generators of either stationary or portable type. The ball type of check valve is found to give better service than any other mechanical type of check valve. The brass or bronze two hundred pound pressure ball check valve, on the present market, is found to have the ball and seat accurately machined and fitted and to be durable as a gas flow interrupter. The three quarter inch ball check valve is found to be a suitable size for small generators designed to furnish acetylene for one welding torch for ordinary repair shop welding. The one inch size check valve suitable for a generator designed to furnish acetylene for one to three welding torches or cutting torches in ordinary welding or cutting. In generators adapted to furnish acetylene for a number of welding torches, I prefer to use a liquid type of interrupter such as shown in Figs. 14 and 15. This type of interrupter while not as violent on the flow is more suitable than the mechanical check valve, in that it will fluctuate the pressure of a small flow of acetylene as well as a large flow, while the mechanical valve of such size as will fluctuate the pressure of a large flow of acetylene fails at times to operate properly in a small flow as when only one welding torch with a small burning tip is being used, due to wear or particles of some nature lodging on the

valve or the valve seat, which hold the valve slightly open allowing a small flow of acetylene to pass without operating the valve.

The liquid form of interrupter shown in Fig. 14 comprises an upright cylinder 46, having top and bottom end closures 46A and 46B, forming a tank adapted to hold a quantity of water or other suitable liquid 47, in its lower end portion. A comparatively small cylinder 48, is disposed centrally within the tank 46 and has its upper end hermetically secured to the under side of the closure 46A. The lower end 48A, of the cylinder extends down into the liquid 47 to a point near the bottom 46B of the tank. The acetylene outlet pipe 26 has its lower end connected with the closure 46A so as to be in communication with the cylinder 48. A second pipe 49, is connected with the closure 46A so as to communicate with the annular space 46B, in the upper portion of the tank 46 and leads to the vibrator 31. The annular space 46B of the tank 46 communicates with the usual flash-back safety tank 35 through the horizontal check valve 34A, and the downturned pipe 35A, which is disposed within the flash-back tank. The valve 34A opens to permit a flow of acetylene from the interrupter tank into the flash-back tank 30 and closes against its return. In operation, acetylene from the outlet pipe 26 flows into the cylinder 48 forcing the liquid 47 out of the lower end of the cylinder into the tank 46, which raises the liquid level in said tank 35 to a point indicated by the dotted line 50. From the lower end 48A of the cylinder acetylene flows upward through the annular column of liquid into the annular space 46B between the cylinder and the wall of the tank 46, hence through the check valve 34A into the flash-back tank 35. Acetylene flows from the flash-back tank through the cut-off valve 38 into the torch line, not shown. By reason that volume of liquid from the lower end of the cylinder 48 being held in the lower end of the space 46B by the acetylene flow, having a tendency to flow back into the said cylinder against the acetylene flow, fluctuates the pressure at which the acetylene flows in space 46B which energizes the vibrator through the medium of the pipe 49.

The interrupter shown in Fig. 15 consists of a relatively large U shaped tube 51, having end closures 51A and 51B. The acetylene outlet pipe 26 connects with one end of the tube through the closure 51A and the pipe 49 leading to the vibrator connects with the other end of the tube through the closure 51B. Enough liquid 47 is placed in the tube to fill the bend portion and upward to the fill plug 52C, forming a kind of seal that separates the gas spaces 52 and 53. In operation, acetylene from the outlet pipe 26 flows into the space 52 forcing the liquid

47 in that portion of the tube around the bend which raises the column upward into the space 53 to a height indicated by the dotted line 50C. This increases the space 52 downwardly to a level with the upper portion 51D, of the tube's bend, from which point acetylene flows around the bend and upward through the column of liquid into the space 53. From space 53 acetylene flows through the horizontal check valve 34A into the flash-back tank, not shown, and on to the point of consumption. The interrupter tube having greater carrying capacity than its inlet or outlet, retards the acetylene flow in the spaces 52 and 53 considerably. The liquid in the bend portion of the tube functioning as a seal between said gas spaces resists the acetylene flow to an extent that it requires some reduction of the pressure in space 53 for acetylene in space 52 to break through the seal. When the seal is broken acetylene rushes into space 53 in such volume that immediately fills the latter space to a pressure approximately equal to that in space 52, consequently allowing the seal to close. The closing of the seal is only momentary as it is broken again when some of the acetylene flows out of the space 53 into the flash-back tank and the operation occurs repeatedly while acetylene is being used. The frequency of operation depending on the carrying capacity of the tube 51 and the rate at which acetylene is consumed. It will be seen that the liquid 47 is oscillated in the bend portion of the tube under influence of a flow of acetylene and the pressure in space 53 is accordingly fluctuant which energizes the vibrator through the pipe 49.

The degree of pressure change in the acetylene flow should be no greater than that required to provide energy enough to shake the feed valve when the latter is in feeding position and it will not be necessary to shake the feed valve harshly to get a regular flow of carbide. Pressure waves extend to the welding flame at the torch and if too high, will fluctuate the proportion of acetylene in the mixture of the gases to a point that will be objectionable. When the mechanical valve alone is used as an interrupter the degree of pressure change in the flow may be regulated somewhat by the flexibility and sensitiveness of the vibrator diaphragm. The greater the area of the vibrator diaphragm the more sensitive the vibrator. And should pressure waves in the acetylene flow seem too high for good operation of the torch, they may be reduced somewhat by using a less sensitive vibrator. The liquid type interrupter will usually require a sensitive vibrator.

While I have shown my invention applied to an acetylene generator in various ways, it may be noticed that in each of the several generators embodying my improvements that have been described the outward acetylene

flow is conditioned to provide a form of energy that may be used to excite a medium which is connected to effect the agitation of carbide in the vicinity of the feed valve and outlet of the carbide container; it will be manifest to persons skilled in the art that many changes may be made in the general arrangement and configuration of the vibrating medium as well as the interrupting medium and slight changes in the mode of operation of same within the scope of the appended claim, without departing from the spirit of the invention; it is, therefore, to be understood that this invention is not to be limited to the details described and shown.

What I claim is:—

In a carbide agitator for an acetylene generator, said generator having an acetylene outlet pipe and a carbide feed valve, an acetylene flow interrupter connected with said outlet pipe, said interrupter provided to interrupt the acetylene flow through said outlet pipe for operating a diaphragm vibrator, said vibrator having tubular connection with the outlet pipe and also being connected with said feed valve so as to agitate the valve and carbide in the vicinity thereof and yet permit free movement of the valve in regulating the feeding of carbide.

30 HERBERT G. IRWIN.
